SHOE CONSTRUCTION

Stanley P. Lovell, Newtonville, and Frank H. Russell, Needham, Mass., assignors to Beckwith Manufacturing Company, Dover, N. H., a corporation of New Hampshire

Application February 21, 1941, Serial No. 380,026

1 Claim. (Cl. 36—77)

Our invention relates to the construction of footwear and especially to the stiffened or reinforced areas of shoe uppers. By our invention a shoe having a box toe or counter of relatively indestructible quality is produced and this with a definite speeding up in the time necessary to last the shoe upper. In another aspect our invention comprises a novel composite lining fabric including a band or bands of stiffening compound bonded thereto and having the latent capacity of being readily rendered plastic and adhesive in the shoe-making process. Our invention includes within its scope the novel shoe structure herein shown as produced by carrying out the process of our invention.

We are aware of U. S. Patent No. 2,009,291 issued July 23, 1935, to Ferguson and Hickler disclosing a shoe in which the integuments of lining and upper material are filled with a liquified material later susceptible of hardening in situ. In their invention the customary stiffening blanks are omitted and adequate stiffness is obtained by the stiffening compound itself. There are serious practical difficulties however in requiring the latter to apply a liquid stiffening solution to both lining and upper at this stage of the shoe making process and in maintaining the solution at the proper consistency. An objectionable delay is thus incurred before the solution dries enough to permit the upper to be pulled over. We overcome the practical shoemaking difficulties and expense of the process of that patent and yet produce a shoe of finer wearing and style qualities.

In carrying out our invention we may select any commercial shoe lining material preferably in sheet form capable of being rolled or coiled. With a doctor knife or other suitable distributing means we apply to one surface of such goods one or more lengthwise bands as a coating or an impregnation of liquified stiffener compound. The width and positioning of our bands will vary, depending on the size and type of footwear in which the lining is later to be employed. For example, for a man's standard shoe shoemaking requirements would be best served by applying to goods a yard wide three continuous lengthwise bands each $3\frac{1}{4}$ " wide leaving two central untreated bands each 7" wide and two marginal untreated bands each 6" wide.

The doctor knife used as an applicator of the compound may be oscillated to produce a wavy movement and thus a serrated or scalloped margin to the treated bands, or we may so taper the doctor knife that a smaller deposit of compound

is effected at the margins of the treated areas whereby a scarf effect is produced.

The compound used to stiffen the bands or areas may vary within certain limits. For cheaper shoes we may employ water dispersable compounds such as starch, dextrine, glue and sodium silicate, with or without modifying amounts of rubber latex and the like; for better grades of footwear we may elect to use thermoplastic compounds of which the following is typical:

	Per cent
Montan wax	20
Calcium resinate	20
Candelilla wax	20
15 Rosin	30
Rubber	10

For shoes of the best quality, however, we have found a compound consisting of substantially the ingredients set forth in the following formula to be best adapted as a stiffening agency for purposes of this invention:

Ethyl cellulose	pounds	$\frac{1}{2}$
De-waxed gum damar	do	$\frac{1}{4}$
25 Toluene	fluid ounces	13
Acetone	do	57

30 We coat or impregnate the bands with the selected stiffening compound whereupon the web is dried and rolled into a roll or coil for shipment to the shoe factory.

The shoemaker lays his patterns or dies for vamps, for example, on the fabric employing a full-length vamp and laying his die on the cloth in such manner that it intrudes into the stiffened area to the desired extent. For example, if he wishes to merely have in his finished shoe an "end" box toe he will lay his die or pattern upon the fabric to include only the extreme tip within the prestiffened area; if he desires a normal box toe in his finished shoe he will employ all, or the major part of the prestiffened area within the scope of his die.

45 The died-out lining blanks for the vamps, quarters or other parts, cut to include the desired stiffened area within them, we now assemble with the upper material, such as leather, satin and the like. We prefer to assemble these in such a manner that the stiffening coating on the lining is located within the upper, that is, facing the flesh or inner face of the upper leather. This assembly may be accomplished with rubber adhesive, paste or stitching.

50 The shoe is now ready for lasting and may be pulled-over at room temperatures or, in the case

of tough upper materials the forepart or rearpart may be steamed or moistened. At the secondary lasting, where such is employed, steam or solvent may be used in the well-known manner to produce complete conformability to the last.

The uppers may be perforated very conveniently after stitching as only two plies or layers of upper material are involved, the prestiffened lining further serving to produce clean outlines.

Our invention is equally suitable for plain-toe or cap-toe shoes. In the latter case the pattern is cut with exactly sufficient prestiffened area included to match or mate with the line of cap-toe tip stitching.

It is obvious that in shoes made by our process the stiffener constitutes an integral part of the lining and that the clicker-die, for example, accurately predetermines where the supported or stiffened area in the finished shoe will be located. Further there is no chance for malpositioning in the pulling-over machine as no slippage or disturbance can force the stiffener out of correct location.

These and other features of our invention will be best understood and appreciated from the following detailed description of a preferred manner of carrying out the invention as illustrated in the accompanying drawing, in which

Fig. 1 is a plan view of a sheet of lining fabric of our invention, showing a vamp lining cut therefrom,

Figure 2 is a view of an assembled vamp and lining,

Fig. 3 illustrates a perforated lined vamp, and

Fig. 4 is a fragmentary sectional view of a lasted shoe in which is incorporated the lining of our invention.

The lining fabric may comprise any suitable woven textile lining fabric such for example, as that disclosed in U. S. Letters Patent No. 2,088,158, granted July 27, 1937, on an application of Henry M. Spelman, and like the lining fabric therein disclosed it may be coated on one surface with a rubberized compound including vulcanizing and accelerating ingredients. This lining fabric is obtainable in sheets of any desired width and length. To the treated surface of this fabric are now applied several continuous lengthwise bands 11 of stiffening compound. Two of such bands are shown in Fig. 1 but the number and spacing is optional and will depend upon how the sheet is to be cut up. These bands, as herein shown, may be of the wax-resin-rubber compound of the formula given above, applied in molten condition by any suitable spreading device. In cooling, the molten band to some extent enters the surface interstices of the fabric and in hardening becomes firmly bonded to the fabric. The band herein shown is substantially transparent and may increase the thickness of the sheets by .010" to .012", while if forcibly stripped from the fabric, the band will be found to measure approximately .015" in thickness. It is dry, normally non-adherent or non-tacky, flexible and has considerable resilient stiffness. While I prefer to employ a lining fabric with a treated surface of the character disclosed because there is a favorable reaction or at least compatible relationship between the coating of the fabric and the material of the applied band, it is within the scope of the invention to employ lining fabric without special surface treatment or with any desired sizing.

As suggested in Fig. 1 a vamp lining has been die cut of the composite sheet in such location

as to include a portion of the band 11 in the area of its tip. Thus we form to exact size a shoe lining part ready to be assembled directly in the upper of a shoe and containing as an integral part thereof a band or layer of stiffening material normally dry and hard but having a latent capacity of softening when heated.

The vamp lining 12 may now be pasted or cemented to the outer integument 13 of the upper, and this of course, may be of any desired material, but herein indicated as being leather. If it is desired to employ the vamp in a perforated shoe it is desirable to cement the composite lining blank securely, in face to face contact with the flesh side of the vamp 13 and having been thus prepared the composite vamp may be perforated as suggested in Fig. 3.

Having assembled the upper, which now includes the composite lining of our invention, it may be pulled over in the usual manner without the necessity of employing any separate box toe stiffener blank and thus is eliminated from the shoemaking process the entire burden of providing and handling separate stiffener blanks. For this is substituted a single composite sheet requiring no more attention in its preparation and handling in the shoe upper than the lining which is customarily employed. All danger of a misplaced stiffener blank is avoided and the location of the stiffened area is insured with greater accuracy and greater compactness of structure than has ever been possible before.

Again, the operation of pulling-over, which is generally limited in men's shoes to 250 pairs per eight-hour day, is seriously retarded by the time consumed in picking up and placing each individual box toe in the pocket formed in the upper, not to speak of the preliminary softening of these blanks. By employing our invention one operator can pull-over about 720 pairs per eight hour day. Not only does he increase his output but the quality of his work is more uniform and, since his production is consumed in matched or mated pairs, this is of vital importance.

When the pulled-over upper goes to the lasting operation the outer integument may be temporarily turned back and the composite lining subjected to moist or dry heat so that the band 11 is temporarily rendered limp, entirely plastic and adhesive. The toe lasting operation is carried out with the lining in this condition and in the lasted upper the coated area of the lining will be bonded to the outer integument and the fine lines of the last will be reproduced with accuracy and precision.

We have mentioned the advantage of employing our novel composite lining in a perforated upper because in this style of shoe it is particularly desirable that no displacement of a stiffening blank should occur after the upper has been perforated. The novel lining of our invention positively eliminates this danger.

It will be understood from the foregoing discussion that the wax-resin-rubber stiffening compound referred to is but one example, although the best now known to us, of a heat-responsive thermoplastic or thermo-setting compound. The cellulose-gum-acetone compound is, similarly one illustration of a solvent responsive stiffening compound. This compound may be applied to the lining fabric as a liquid solution in acetone. It dries into a band adhering to the sheet material and having a non-tacky exposed surface, and may be temporarily softened and rendered adhe-

sive in the assembled upper by being moistened with acetone.

The starch-dextrine-glue compound above mentioned is an example of a stiffening compound which may be applied to the lining fabric in a water solution and which may be temporarily softened and rendered adhesive by moisture in the assembled upper.

The various formulae above set forth are the best now known to us, but they may be varied and other ingredients substituted without departing from the scope of the invention. For example, in the cellulose-gum-acetone compound instead of ethyl cellulose we may employ vinyl acetate, cellulose acetate, pyroxylin, polymeric styrene or the equivalent. For de-waxed gum damar we may employ rosin gum, ester gum, pon-

25

30

tinak, loba, or equivalent gum substances. For toluene we may substitute benzol or a suitable aromatic hydrocarbon. For the acetone ingredient we may substitute ethyl or methyl alcohol, ethyl or methyl ketone, or the equivalent.

A lining having a stiffening band or zone of the type above discussed may be temporarily softened in the shoemaking process by any suitable volatile solvent such as acetone or ethyl acetate.

While for reasons of convenience it is preferable that the applied bands shall be dry, flexible and non-adherent, because in that case the goods may be rolled up, stored and handled like so much yard

goods, these characteristics are not essential features of our invention. For example, the applied bands may be normally so stiff that it is more convenient to handle the lining material in sheets instead of rolling it. While a normal or initial non-adherent band surface is desirable that feature too is of only secondary importance and should occasion arise the composite lining material may be handled with suitable separator sheets.

Our novel process of making shoe lining blanks is not claimed herein but forms the subject matter of our copending divisional application Serial No. 538,390 filed June 2, 1944.

Having thus disclosed our invention and described in detail certain specific embodiments of our novel composite lining and of its manner of use, we claim as new and desire to secure by Letters Patent,

A shoe having an upper comprising an outer integument and a lining bonded thereto in a limited area and forming therewith an integral composite sheet, and a layer of solvent-responsive stiffening material comprising substantially ethyl cellulose $\frac{1}{2}$ lb., dewaxed gum damar $\frac{1}{4}$ lb., toluene 13 oz., acetone 57 oz., supplying a bond between the outer integument and the lining.
